(57) **CLAIM**

The ornamental design for a snap mobile phone case, as shown and described.

DESCRIPTION

FIG. 1 is a three-quarter perspective view of a mobile phone, a top portion of the snap mobile phone case, and a bottom portion of the snap mobile phone case disconnected;

FIG. 2 is a three-quarter perspective view of the mobile phone encased in the top portion of the snap mobile phone case with the bottom portion of the snap mobile phone case disconnected;

FIG. 3 is a front view of the mobile phone encased in the top portion of the snap mobile phone case with the bottom portion of the snap mobile phone case disconnected;

FIG. 4 is a left-side view of the mobile phone encased in the top portion of the snap mobile phone case with the bottom portion of the snap mobile phone case disconnected;

FIG. 5 is a rear view of the mobile phone encased in the top portion of the snap mobile phone case with the bottom portion of the snap mobile phone case disconnected;

FIG. 6 is a right-side view of the mobile phone encased in the top portion of the snap mobile phone case with the bottom portion of the snap mobile phone case disconnected;

FIG. 7 is a top view of the mobile phone encased in the top portion of the snap mobile phone case with the bottom portion of the snap mobile phone case disconnected;

FIG. 8 is a three-quarter perspective view of the mobile phone encased in the top portion of the snap mobile phone case with the bottom portion of the snap mobile phone case connected;

FIG. 9 is a front view of the mobile phone encased in the top portion of the snap mobile phone case with the bottom portion of the snap mobile phone case connected;
FIG. 10 is a left-side view of the mobile phone encased in the top portion of the snap mobile phone case with the bottom portion of the snap mobile phone case connected;
FIG. 11 is a rear view of the mobile phone encased in the top portion of the snap mobile phone case with the bottom portion of the snap mobile phone case connected;
FIG. 12 is a right-side view of the mobile phone encased in the top portion of the snap mobile phone case with the bottom portion of the snap mobile phone case connected;
FIG. 13 is a top view of the mobile phone encased in the top portion of the snap mobile phone case with the bottom portion of the snap mobile phone case connected;
FIG. 14 is a three-quarter perspective view of the top portion of the snap mobile phone case with the bottom portion of the snap mobile phone case disconnected;
FIG. 15 is a front view of the top portion of the snap mobile phone case with the bottom portion of the snap mobile phone case disconnected;
FIG. 16 is a left-side view of the top portion of the snap mobile phone case with the bottom portion of the snap mobile phone case disconnected;
FIG. 17 is a rear view of the top portion of the snap mobile phone case with the bottom portion of the snap mobile phone case disconnected;

FIG. 18 is a right-side view of the top portion of the snap mobile phone case with the bottom portion of the snap mobile phone case disconnected;
FIG. 19 is a three-quarter perspective view of the top portion of the snap mobile phone case with the bottom portion of the snap mobile phone case connected;
FIG. 20 is a front view of the top portion of the snap mobile phone case with the bottom portion of the snap mobile phone case connected;
FIG. 21 is a left-side view of the top portion of the snap mobile phone case with the bottom portion of the snap mobile phone case connected;
FIG. 22 is a rear view of the top portion of the snap mobile phone case with the bottom portion of the snap mobile phone case connected;
FIG. 23 is a right-side view of the top portion of the snap mobile phone case with the bottom portion of the snap mobile phone case connected;
FIG. 24 is a top view of the top portion of the snap mobile phone case with the bottom portion of the snap mobile phone case connected; and,
FIG. 25 is a bottom view of the top portion of the snap mobile phone case with the bottom portion of the snap mobile phone case connected.
The broken lines in the drawings represent unclaimed environmental subject matter.
